SNOWDEN B. REDFIELD, OF EASTON, PENNSYLVANIA, ASSIGNOR TO INGERSOLL-RAND COMPANY, OF JERSEY CITY, NEW JERSEY, A CORPORATION OF NEW JERSEY.

WATER VALVE FOR COMPRESSORS.

Application filed May 16, 1923. Serial No. 639,260.

To all whom it may concern:

Be it known that I, SNOWDEN B. REDFIELD, a citizen of the United States, a resident of Easton, county of Northampton, and State 5 of Pennsylvania, have invented a certain Water Valve for Compressors, of which the following is a specification, accompanied by drawings.

This invention relates to compressors, but 10 more particularly to means for controlling the supply of cooling water to a compressor.

The primary object of the present invention is to enable the cooling water supplied to a compressor to be automatically controlled 15 by the speed of the compressor so that cooling water will be admitted after the compressor has attained a sufficient speed, and shut off as the compressor stops.

A further object of this invention is to 20 enable the cooling water supplied to the compressor to be controlled by an unloader and pilot valves, or by pilot valves alone, which automatically control the operation of the water valve.

25 Further objects of the invention will hereinafter appear, and the invention is shown in one of its preferred forms in the accompanying drawings, in which—

Figure 1 is a side elevational view partly 30 in longitudinal section of a compressor unit with the water valve connected thereto, and

Figure 2 is a side elevational view partly 35 in longitudinal section of a compressor unit, and showing another manner for controlling the operation of the water valve.

Referring to the drawings, the compressor A has a cylinder B, inlet valves C and discharge valves E communicating with the discharge chamber F. The discharge chamber F is in communication with the discharge line G. The piston H is adapted to reciprocate in the cylinder B and to be driven by some suitable source of power, as an electric motor, (not shown). A cooling water jacket J partially encloses the cylinder B, and the inlet line K and discharge line L connected thereto provide for circulation of the cooling water around the cylinder B.

A discharge unloader O as shown in Figure 1 is connected to the discharge line G and is provided with a main check valve P adapted to be forced to its seat Q in the partition R by the combined pressure of the fluid in the receiver S and the coil spring T,

when the compressor is idle. The check valve P is guided on the cap screw U, which screw also serves as a closure for one end of the unloader O.

A relief valve V is adapted to be moved to its seat W in the wall X of the unloader casing to close the atmospheric vent Y in the casing extension Z. The relief valve V has limited movement in the piston a which is provided with an enlarged head b, adapted to be forced to its seat W by fluid pressure admitted in the rear of the head b from the main discharge valve chamber d.

The operation of the unloader O is controlled in this instance, by pilot valves A' and B' connected to the compressor cylinder B adjacent each end thereof. The unloader and pilot valves shown in the drawing are of the same construction and operate in similar manner to those shown and described in my co-pending application Serial No. 639,259, filed May 16, 1923. Detailed description thereof is therefore deemed unnecessary here, and only the essential details of operation and construction of the unloader and pilot valves will be herein described sufficient to enable those skilled in the art to which this invention relates to understand the construction of same.

The pilot valves A' and B' which are identical in their construction, are composed of upper casing sections a' and lower casing sections b', held together in any suitable manner. A piston c' has an enlarged head d' which is adapted to be forced to its seat e' by pressure fluid from the compressor cylinder B. A plunger f' has limited movement in the piston c' over a pin g', which passes through the transverse aperture h' in the plunger, and has its ends secured in the piston c'. The plunger f', urged forwardly by the comparatively heavy coil spring f', is adapted to bear against and seat the ball check valve j', which controls the atmospheric vent h', in the casing section a'. The ball valve j', urged from its seat by the coil spring g' is spaced from the ball check valve o' by the spacer pin p'.

The check valve r' having a small hole s' is prevented from being moved too great a distance from its seat by a coil spring t', and controls or retards the passage of pressure fluid from the lower casing section b' to the compressor cylinder, through the port

w'. The number of washers *v'* located in the lower casing section *b'* may be varied, as required, to increase or decrease the volume under the piston *c'* to control the movement of the piston *c'*.

10 The main valve chamber *d* of the unloader is connected to the top of the pilot valve *A'*, by the pipe or tube *w'*, and the space in the rear of the unloader piston *a* in the casing extension *Z* is connected to the port *x'* of the pilot valve *B'* by a pipe *w'*. The top of the pilot valve *B'* is in communication with the port *y'* of the pilot valve *A'* by the pipe or tube *z'*.

15 The unloader *O* and pilot valves *A'* and *B'* are preferably connected "in series", as above described, so that on starting, sufficient fluid pressure is admitted behind the enlarged head *b* of the piston *a* to force it 20 to its seat *c* thereby closing the relief valve *V* and shutting off the flow of pressure fluid from the main discharge valve chamber *d* to atmosphere through the vent *Y*. This 25 operation does not take place until the piston *H* has attained a pre-determined speed, as pointed out in my co-pending application.

30 On stopping, the differential pressure created in the cylinder *B* on both sides of the piston *H* will actuate the pilot valves *A'* and *B'*, in such a manner that pressure fluid will be relieved to atmosphere from behind the enlarged head *b* of the piston *a*. Any pressure fluid remaining in the cylinder *B* will pass to atmosphere through the vent *Y* in the extension *Z* of the unloader casing, so that the compressor is completely 35 unloaded when the compressor piston *H* finally stops.

40 It is highly desirable to regulate the flow of cooling water to the cylinder jacket *J* so that on starting of the compressor, cooling water will be admitted to the jacket and, on stopping, the supply of cooling water will be automatically shut off. In 45 accordance with my invention, I provide a water valve *e* having a casing *f* which is closed at its top by a plate *g*. A piston *h*, normally held in its upward position by a coil spring *j*, is adapted to be actuated in 50 one direction in the casing *f* by fluid pressure, and controls the movement of a stem *k*, which has one end in contact with the inside of the piston. The stem *k* is guided in the wall *o*, and carries a valve head *p* at its 55 lower end. The valve head *p* cooperates with the valve seat *q* for shutting off and preventing the flow of cooling water to the jacket *J* of the compressor. A coil spring *r*, one end of which seats against the cap screw *s* and the other end of which bears against the under side of the valve *p*, urges the valve head *p* to its seat *q*.

60 A pipe *t* is connected at one end to the plate *g* of the water valve *e*, and at its other end to the main discharge valve chamber *d*

of the unloader *O* so that a communication is formed between the main discharge valve chamber *d* and the water valve casing *f* above the piston *h*. For controlling the amount of cooling water flowing through the inlet line *K* to the cylinder jacket *J*, I provide any suitable valve *u* in the inlet line *K*. This valve also controls the amount of cooling water passing through the water valve *e*.

70 When the compressor is under load and the piston *H* has attained a sufficient speed, pressure fluid is admitted from the main discharge valve chamber *d* through the pilot valves *A'* and *B'* to the extension *Z* of the 75 unloader casing, rearwardly of the piston *a*. The enlarged head *b* of the piston *a* is thereby moved to its seat *c*. At the same time, the relief valve *V* is moved to its seat *W*, and closes the passage of pressure fluid from the main discharge valve chamber *d* to atmosphere through the vent *Y*. When this condition has been reached, pressure fluid flows through the pipe or tube *t* to the water valve *e* above the piston *h*. The piston *h*, and the stem *k* are thereupon forced 80 downwardly compressing the coil spring *j*. The valve head *p*, carried by the stem *k*, is thereby unseated from its seat *q*, and the 85 passage of cooling water from the inlet line *K* to the cylinder jacket *J* is permitted.

90 As the compressor stops, the pressure in 95 rear of the enlarged head *b* of the unloader piston *a*, will be relieved to atmosphere by the alternate operation of the pilot valves *A'* and *B'*. The pressure in the main discharge valve chamber *d* is then sufficient to 100 unseat the relief valve *V* and move the unloader piston *a* rearwardly, so that the pressure fluid in the discharge valve chamber *d* 105 may be relieved to atmosphere through the vent *Y*. The pressure fluid in the pipe or tube *t* above the piston *h* also passes to atmosphere through the vent *Y* and the coil spring *j* moves the piston *h* upwardly, seating the valve head *p* and preventing further 110 flow of cooling water through the inlet line *K* to the cylinder jacket *J*.

115 The cooling water supplied to the cylinder jacket *J* is automatically controlled by the speed of the compressor so that cooling water is admitted to the cylinder jacket on the starting of the compressor and completely shut off as the compressor stops.

120 There are certain cases where a compressor is required to start under relatively low air pressure, pumped up to some final pressure considerably higher. The motors for operating these compressors are designed for the power at higher pressures. In such cases, especially with direct current motors, it is readily possible to start the compressor 125 without any starting unloader.

130 In such cases, especially in places where water is expensive, it is advisable to control

the water to start and stop in unison with the compressor. For this service, it is possible to apply the water valve without the starting unloader. In the modification 5 shown in Figure 2, I have shown a water valve *e* operating by the pilot valves which are connected "in series" to the water valve. The pilot valves, in this instance, operate directly upon the water valve to admit the 10 cooling water when the compressor starts, and to shut off the flow of water when the compressor stops.

One starting of the compressor, a differential, pressure is created in the compressor 15 cylinder *B*. This differential pressure prevents the passage of fluid from the discharge line *G* of the compressor to the water valve *e* above the piston *h*. When the compressor is starting, and the piston is moving in the 20 direction of the arrow in Figure 2, pressure fluid from the compressor cylinder moves the piston 2 and plunger 3 of the pilot valve *A'* upwardly and seats the ball check 4, thereby closing the passage of fluid at at- 25 mosphere through the vent 5, in the pilot valve casing. At the same time, the ball check valve 6 is unseated by the spacer pin 7. As the compressor piston *H* is on its suction stroke relative to the pilot valve *B'*, 30 the piston 8 and plunger 9 therein move downwardly, due to the flow of pressure fluid from the lower section of the pilot valve to the compressor cylinder, the entrance of atmospheric air through the vent 35 10 in the pilot valve casing and the coil spring 12. The ball check valve 11 is seated by the coil spring 12, thus shutting off the passage of pressure fluid from the discharge line *G*. The ball check valve 14 is unseated 40 by the coil spring 12 acting against the ball valve 11 and spacer pin 13 thereby permitting pressure fluid from the water valve *e* to pass through the pipe or tube 15 to atmosphere through the vent 10 in the side of 45 the pilot valve casing.

As the compressor piston moves in the opposite direction, the operation of the pilot valves above described is reversed and no pressure fluid is admitted to the piston *h* 50 of the water valve *e* from the discharge line *G* until the compressor has attained a sufficient speed, so that the pistons and plungers of the pilot valves are held in their forward position and the check valves 6 and 55 11 in the pilot valves *A'* and *B'* respectively are held unseated. When this condition has been reached, passage of fluid is permitted from the discharge line *G* successively through the pipe 16, pilot valve *A'*, pipe 17, 60 pilot valve *B'* and the pipe 15, to the water valve *e* moving the piston *h* downwardly and unseating the valve head *p* to permit the flow of cooling water to the jacket *J*.

As the compressor is stopping, the alter- 65 nate rising and falling of the plungers and

pistons in the pilot valves *A'* and *B'*, alternately permit pressure fluid from the water valve *e* to pass to atmosphere through the vents 5 and 10 in the pilot valves *A'* and *B'* respectively, and the pressure fluid from the 70 discharge line *G* having been cut off alternately by the ball valves 6 and 11 thereby relieving the pressure above the piston *h* of the water valve to permit the coil springs *j* and *r* to move the piston *h* and stem *k* upwardly and thus move the valve head *p* to its seat.

The pilot valves thus serve to cut off and relieve the pressure from the piston *h* in the water valve *e* on stopping of the compressor, 80 and to admit pressure fluid to the water valve after the compressor has attained a sufficient speed.

I claim:

1. In a compressor, the combination with 85 a valve adapted to be connected to a compressor for controlling the supply of cooling water to the compressor cylinder, of a plurality of pilot valves in communication with the discharge line of the compressor 90 and connected in series with the water valve, whereby cooling water is admitted to the compressor cylinder after the compressor has attained a predetermined speed, and shut off as the compressor stops. 95

2. In a compressor, the combination with a valve adapted to be connected to a compressor for controlling the supply of cooling water to the compressor cylinder, of a plurality of pilot valves in communication with the discharge line of the compressor and connected to the compressor cylinder for controlling the opening and the closing of the water valve in accordance with pressure in the compressor cylinder. 100

3. In a compressor, the combination with a valve adapted to be connected to a compressor for controlling the supply of cooling water to the compressor cylinder, means for regulating the amount of water flowing past the valve, of a plurality of pilot valves in communication with the discharge line of the compressor and connected in series with the water valve, whereby cooling water is admitted to the compressor cylinder after the compressor has attained a predetermined speed, and shut off as the compressor stops. 110

4. In a compressor, the combination with a water valve for jacket water, comprising a piston, a stem bearing against and adapted to be moved by the piston, a valve head on the stem, a valve, a valve seat, means connected to the valve head tending to force the valve head to the seat, means within the piston tending to seat the valve head, of a plurality of pilot valves in communication with the discharge line of the compressor, and connected in series to the water valve. 120

5. The combination comprising a com-

pressor, unloading means for said compressor, cooling water control means, means for allowing pneumatic actuation of both of said means, and means whereby said latter means is controlled by the speed of said compressor.

6. The combination comprising a compressor, a receiver, unloading means for said compressor, cooling water control means,

means connecting both of said means to said receiver to be actuated by fluid under pressure including means common to both of said devices, and a speed responsive controlling device connected to said common means.

In testimony whereof I have signed this 15
specification.

SNOWDEN B. REDFIELD.
